UNITED STATES PATENT OFFICE.

WILLIAM H. KREMSE, OF FREMONT, NEBRASKA.

AUTOMATIC OILER FOR STOCK.

1,186,913.

Specification of Letters Patent. Patented June 13, 1916.

Application filed April 3, 1916. Serial No. 88,474.

To all whom it may concern:

Be it known that I, WILLIAM H. KREMSE, a citizen of the United States, residing at Fremont, in the county of Dodge and 5 State of Nebraska, have invented certain new and useful Improvements in Automatic Oilers for Stock, of which the following is a specification.

This invention relates to an automatic 10 oiler for use in applying medicated liquids to hogs, sheep or cattle for destroying parasites or curing skin diseases, and has for its object, broadly, to provide such a construction that a positive operation may be effected for applying the liquid forcibly to 15 the body of the animal.

The invention includes a passageway through which the animal may travel, and a door or gate arranged to partly obstruct 20 the passageway, and an ejector member for applying the liquid, operative by the swinging movement of the gate when the animal makes contact therewith in the act of moving through the passageway.

25 The device has been found to be particularly useful in connection with the raising of hogs and sheep, the application of the liquid being positive in operation since the door or gate may partly obstruct a way between feeding yards, through which the 30 stock will readily pass.

The invention consists of the novel construction, combination and arrangement of parts as described herein and claimed, and 35 as illustrated in the accompanying drawing, it being understood that changes in form, size, proportion and minor details may be made within the scope of the invention as determined by the appended claims, without 40 sacrificing any of its advantages.

In the accompanying drawing, illustrating one embodiment of the invention, Figure 1 is a view in side elevation of an oiler for stock. Fig. 2 is an enlarged detail, partly 45 in section, relating to Fig. 1, the ejector and receptacle being partly broken away. Fig. 3 is a vertical section on line 3—3 of Fig. 1. Fig. 4 is a vertical section on line 4—4 of Fig. 1, looking to the ejector and receptacle. 50 Fig. 5 is a view of the ejector in longitudinal section. Fig. 6 is a plan view of a segmental actuating plate. Fig. 7 is a perspective view of one of the crank shafts. Figs. 8 and 9, respectively, are side and end views of the 55 same, Fig. 9 showing the free end of the

finger on said crank shaft. Fig. 10 is a plan view of a tread block employed.

Referring now to the drawing for a more particular description, I provide a doorway 11 which may have any desired height and width depending upon the kind of stock to be treated, and while any suitable material may be used to provide a rectangular frame or doorway, I have employed the vertical tubular sections 12 and 13 to advantage, 60 these being connected at their upper ends with the horizontal, tubular sections 14 and 14', the lower ends of said vertical sections being secured to a suitable base or platform 15. The frame thus described provides a 65 structure which is strong and portable, and comparatively inexpensive.

I provide a gate of rectangular form, preferably consisting, in part, of the top and bottom tubular sections 16 and 17, and side 75 tubular sections 18 and 19, their ends being suitably joined or connected to provide a rigid structure. In order that the gate will remain normally closed and, normally, will be disposed in horizontal alinement with the standards or posts 12 and 13, I provide for the post 12 a tread block 20 having an inclined, annular trackway 21 disposed equidistant from the longitudinal axis of said post, upon which trackway the wheel 22 80 may move, said wheel having bearings in a block 23 which is secured to the gate. The gate is provided with sleeves 24 for engaging loosely the post 12, and it will be understood that when the gate is swung in either 85 direction, it will be elevated for the reason that the wheel will move upwardly upon the annular trackway when the gate swings outwardly, and the gate will move downwardly when swung to a closed position, its 90 weight causing said closing movement, the wheel moving downwardly upon trackway 21, the sleeves 24 sliding upon said post 12. The gate has a width considerably less than the width of the gateway, to provide a 95 comparatively large area, indicated at 25, between the free end of the gate and the post 13, this space being desirable so that it may be seen and that animals will move readily therethrough for causing a swinging movement of the gate. At 26 is indicated a receptacle adapted to contain a supply of medicated liquid, and devices are provided which

operate in such a manner that when an animal causes a swinging movement of the gate, 100 105 110

outwardly, in either direction, quantities of the liquid, either as a limited stream or spray, will be discharged, the arrangement preferably being such that successive charges 5 of the liquid will be applied upon and at different parts of the body of the moving animal.

At 27 is indicated a cylinder provided at its outer and inner ends respectively with 10 screw caps 28 and 29, the cap 29 being provided with a nozzle or screw plug 30 to provide an inclined exit-way or discharge port 31 for liquid, and providing a valve seat 32 for the needle valve 33, the stem 33' of the 15 valve being slidably mounted in the screw-cap 28 and provided with a piston α and provided upon its threaded end, inwardly of cap 28, with an adjusting-nut 34. Any suitable conduit may be provided through which 20 the liquid may move from the receptacle 26 to the cylinder, the bore of pipe 14', as best shown in Fig. 2, being used for this purpose, the liquid moving into the cylinder through an aperture 35 formed in the wall of said 25 cylinder and opening upon the bore of said pipe.

Means are provided for reciprocating the valve stem while an animal is causing a swinging movement of the gate outwardly 30 when moving through the passageway. An actuating plate 36 is provided, said plate being of segmental form and having a transverse curvature so that its ends, at the sides of the tubular section 16 may be disposed 35 somewhat lower than its middle. This plate is mounted midway between its ends upon the tubular section 16 of the gate and suitably secured thereto. As best shown in Fig. 40 6, this plate is provided, to extend upwardly near its curved edge at one side of the tubular section 16 (for convenience called the front side) with a series of projections or teeth 37, these projections being disposed at suitable distances apart in a curved row concentric with the center of the segment or 45 post 12 which is the center of movement for the gate, and said segment is provided with a series of projections or teeth 38, similar to those already described, and disposed in a row concentric with the center of movement of the gate, but somewhat nearer the center than the series of teeth 37, and at the opposite or near side of the tubular section 16.

Secured upon the tubular section 14 of the 50 gate frame is a box 39 which provides bearings for a pair of crank shafts 40 and 41, said crank shaft 40 having an arm a extending transversely therefrom, said arm a being disposed in the plane of and adapted to 55 be engaged by the series of teeth 38, in succession, when the gate swings outwardly at the rear side of the gateway. The crank shaft 41 also is provided with a transverse arm b disposed in the plane of and adapted 60 to be engaged in succession, by the series of

teeth or projections 37 of said plate 36 when the gate has a swinging movement in an opposite direction to that last mentioned.

The crank c of crank shaft 40 is provided with a finger d which is disposed transversely with reference to said crank, the terminal part of said finger d being disposed near the lower end and at the front side of the cylinder 27. Crank c' of the crank shaft 41 is also provided, to extend 75 transversely therefrom, with a finger e , its terminal part being disposed at the opposite or rear side of said cylinder.

Numerals 42 indicate a tilting member of substantially inverted U-shape, the end of 80 each of its arms being provided with a foot piece or buffer, these being indicated, respectively, at 43 and 43', for engagement with the respective fingers d and e . At 44, mounted on the threaded end of the valve stem outwardly of the upper end of member 42, is a second nut, by means of which any upward movement of the tilting member will be communicated to the valve stem 33', the arms of said member 42 sliding in the guide 45 85 which is secured to the cylinder by suitable keepers 46.

In operation, a hog or other animal may cause a swinging movement of the gate in a manner to cause the arm b of the crank shaft 95 41 to engage, in succession, teeth 37 of the plate 36, and each engagement mentioned will cause a part rotation of the crank shaft 41 to effect a swinging movement of the finger e which will elevate the tilting member 100 for lifting the valve from its seat, the liquid thereupon moving out of the discharge port with considerable force, the weight of the metallic parts, such as members 33, 33', 42 and 44 being depended upon 105 for causing a return movement of the valve, forcibly, to its seat for ejecting the liquid from port 31.

Numerals 47 indicate weights with which 110 arms a and b of the crank shafts are provided, so that, after a swinging movement has been effected for one of said arms, by its engagement with a tooth, it will instantly move or swing downwardly to be engaged by the next tooth of the series. Suitable 115 brace rods 48 are provided which extend between the plate 36 and the tubular section 19 of the gate, for the purpose of supporting said plate.

From the description it will be understood that the amount of discharge, while an animal is moving through the gate frame or passage way may be increased or diminished, as may be desired. Member 42, by means of the adjustments mentioned, may 120 be elevated or lowered on the stem 31 to cause, respectively, a decrease or increase of the quantity discharged; also it will be understood that when the teeth of one series 125 are moving into engagement with one of the 130

arms *a* or *b*, the teeth of the other series do not engage either of the arms, the arrangement being such that operation will be effective for spraying or applying liquid from a 5 stationary nozzle or ejector to different parts of the body of the animal while passing through the gateway.

It will be appreciated that if the gate has a rapid swinging movement caused by a 10 rapid movement of the animal, that the intervals of time between the discharges will be correspondingly reduced, so that the discharges of the medicated liquid may be practically applied to different parts of the 15 body of the moving animal.

Having described construction of parts, a further explanation relating to operation is not necessary.

What I claim as new and desire to secure 20 by Letters Patent is,—

1. In devices for the purpose described, a gate provided with concentric rows of projections, a receptacle for containing a medicated liquid, a cylindrical casing having an 25 intake port communicating with the receptacle and provided with a discharge port and a valve seat between said ports, a valve normally disposed on the valve seat and provided with a valve-stem, a tilting-member 30 substantially of inverted U-shape connected with the valve-stem, a pair of shafts each having a part engaging the tilting-member and an arm disposed in the plane of one of the concentric rows of said 35 projections, said gate being adapted to have a swinging movement for moving the projections of one of its concentric rows successively into engagement with the arm of a shaft for causing movements of the tilting- 40 member to cause movements of the valve upon its seat.

2. Devices for the purpose described, comprising, in combination with a passageway, a gate normally obstructing a part of said 45 passageway, and provided with projections, a cylindrical casing provided with a valve and a discharge port controlled by said valve, a liquid container communicating with the cylindrical casing, a tilting-member 50 for controlling said valve, a pair of crank shafts for controlling the tilting-member, said crank shafts being provided with arms disposed in the plane of the projections of the gate, said gate being adapted to have a 55 swinging movement for moving the projections thereof into engagement with an arm of a crank shaft for actuating said valve.

3. In devices for the purpose described, a 60 vertically disposed gate provided with projections, a cylindrical casing provided with a discharge port, an intake port and a valve seat between said ports, a receptacle for containing a medicated liquid in communication with said intake port of the cylindrical 65 casing, a valve normally disposed on the

valve seat and having a stem extending outwardly from the cylindrical casing, a tilting-member disposed stridingly upon the cylindrical casing and connected with the valve stem, a pair of crank shafts each having a 70 part engaging the tilting-member, each of said crank shafts being provided with an arm disposed in the plane of a part of the projections of said gate, said gate being adapted to have a swinging movement for 75 causing engagement of a part of the projections thereof with the arm of a crank shaft for actuating said valve.

4. In combination with a passageway, a gate arranged to normally close a part of 80 the passageway, a segmental plate mounted on the gate and provided with projections, a cylindrical casing having a discharge port adjacent to the gate, a valve for controlling the discharge port and provided with a stem, 85 a liquid container communicating with the cylindrical casing, a tilting-member connected with the valve stem for moving the valve, a crank shaft having a part engaging the tilting-member and having a part adapted 90 to be engaged by the projections of the segmental plate when the gate has a swinging movement in one direction for actuating the tilting-member, and a second crank shaft having a part adapted to be engaged by 95 the projections of said segmental plate when the gate swings in an opposite direction for actuating the tilting-member.

5. In combination, a gate mounted to close a part of a passageway, a plate of segmental form carried by the gate and provided with a series of projections and a second series of projections, a cylindrical casing having a discharge port disposed adjacent to the gate and provided with a valve seat, a liquid container communicating with the cylindrical casing, a valve normally disposed on the valve seat, a tilting-member having a connection with the valve for controlling its movements, a crank shaft connected with the tilting-member and having an arm disposed in the plane of the first named series of projections of said plate, a second crank shaft connected with the tilting-member and having an arm disposed 105 in the plane of the second series of projections of said plate, the operation being that when the gate has swinging movements alternately in opposed directions the projections of said plate will move into engagement with the arms of the crank shafts for actuating the tilting member.

6. In combination, a gate provided with 120 projections and mounted to normally close a part of a passageway, a cylindrical casing having a discharge port disposed adjacent to the gate and provided with a valve seat, a liquid container in communication with the cylindrical casing, a valve normally disposed on the valve seat, a tilting-member 130

having a connection with the valve for lifting it from its seat, a crank shaft engaging the tilting-member and having an arm disposed in the plane of the projections of said gate, said gate being adapted to have a swinging movement for moving its projections into engagement with the arm of said crank shaft for causing a rotatable movement of the

shaft to actuate the tilting member for lifting said valve from its seat.

10

In testimony whereof, I have affixed my signature in presence of two witnesses.

WILLIAM H. KREMSEER.
